CLAIM

The ornamental design for a motorcycle chain guide, as shown and described.

DESCRIPTION

FIG. 1 is a rear perspective view of a design for a motorcycle chain guide according to a first embodiment of the present invention.

FIG. 2 is a front perspective view of the motorcycle chain guide of FIG. 1.

FIG. 3 is a right side view of the motorcycle chain guide of FIG. 1.

FIG. 4 is a left side view of the motorcycle chain guide of FIG. 1.

FIG. 5 is a top view of the motorcycle chain guide of FIG. 1.

FIG. 6 is a bottom view of the motorcycle chain guide of FIG. 1.

FIG. 7 is a front view of the motorcycle chain guide of FIG. 1.

FIG. 8 is a rear view of the motorcycle chain guide of FIG. 1.

FIG. 9 is a rear perspective view of a design for a motorcycle chain guide according to a second embodiment of the present invention.

FIG. 10 is a front perspective view of the motorcycle chain guide of FIG. 9.

FIG. 11 is a right side view of the motorcycle chain guide of FIG. 9.

FIG. 12 is a left side view of the motorcycle chain guide of FIG. 9.

FIG. 13 is a top view of the motorcycle chain guide of FIG. 9.

FIG. 14 is a bottom view of the motorcycle chain guide of FIG. 9.

FIG. 15 is a front view of the motorcycle chain guide of FIG. 9; and,

FIG. 16 is a rear view of the motorcycle chain guide of FIG. 9.

(Continued)

The dashed lines in the drawings illustrate portions of the motorcycle chain guide that form no part of the claimed design.
